UNITED STATES PATENT OFFICE.

CLAUDE D. ENOCHS AND JULIUS J. BARON, OF MINNEAPOLIS, MINNESOTA, ASSIGNEES
TO STREMEL BROTHERS, OF MINNEAPOLIS, MINNESOTA.

METAL WINDOW FRAME AND SASH.

Application filed June 7, 1924. Serial No. 718,671.

To all whom it may concern:

Be it known that we, CLAUDE D. ENOCHS, a citizen of the United States, and a resident of Minneapolis, in the county of Hennepin and State of Minnesota, and JULIUS J. BARON, a citizen of the United States, and a resident of Minneapolis, in the county of Hennepin and State of Minnesota, have invented certain new and useful Improvements in Metal Window Frames and Sashes, of which the following is a specification.

One object of our invention is to provide in a metal window frame a hollow jamb having a vertical tubular well formed in the inner wall thereof to conceal the sash chain.

Another object is to provide in a metal jamb a vertical tubular well having a vertical slot in the outer wall thereof to receive the sash side rail plates.

Another object is to provide an improved form of hollow jamb construction that will allow the ready removal of both sashes.

Another object is to provide a sash guide plate well of small cross-sectional area to reduce the passage of air around the edges of the sash plate.

Another object is to provide in a hollow jamb independent compartments for weights and that portion of the weight chains vertically above the sash side plates.

Another object is to provide an improved form of lintel having a horizontal slot in the bottom wall thereof leading into an enclosed compartment for the upper sash plate.

Another object is to provide lintel and jamb constructions of great rigidity.

Another object is to provide improved means for joining jambs, lintel and sill.

Another object is to provide an improved form of thin sash construction.

Another object is to provide an improved meeting rail between sashes.

Another object is to provide an improved form of pulley block mounting whereby pulleys may be readily replaced.

With these and incidental objects in view, the invention consists of certain novel features of construction and combination of parts, the essential elements of which are hereinafter described with reference to the drawings which accompany and form a part of this specification.

In the drawings Figure 1 is a side eleva-

tion of a window embodying our invention; Figure 2 is a perspective view of one of the upper jamb and lintel connecting castings; Figure 3 is a plan view of one of the removable pulley mounting blocks; Figure 4 is a section taken on the line 4-4, Figure 1; Figure 5 is a section taken on line 5-5, Figure 4; Figure 6 is a section taken on the line 6-6, Figure 1; Figure 7 is a sectional view of the center sill casing taken on the line 7-7, Figure 8; Figure 8 is a section taken on the line 8-8, Figure 7; Figure 9 is a perspective view of one of the sill and jamb connecting blocks.

The window frame consists of a lintel 1, sill 2, and right and left jambs 3, connected by top castings 4 and bottom castings 5, with a center sill casting 6 to reinforce the center of the sill.

The jambs 3 are mounted on the castings 5 and thereby connected to the sill 2, and are preferably formed of flat sheet metal plates.

A vertical metal plate 7 has a lip 8 folded back on itself, as shown in Figure 6, and is then bent at four right angles to form the jamb proper. The metal is further extended by return bend 9, which is extended to form the wall 10, which is bent at right angles to form the wall 11 and again at right angles to form the wall 12, which is bent back on itself at 13 and then formed into the lip 14.

Between the lip 14 and the wall 13 is a plate 15, which is bent at right angles to form the plate 16, which is again bent at right angles to form the plate 17 and again bent at right angles to form the plate 18, a further right angle bend to form the plate 19, a further right angle bend forms the plate 20, a further right angle bend forms the plate 21, which is bent back into a lip 22 and between the lip 22 and the plate 21 is a plate 23, which is bent at right angles and again to form the plate 25, again to form the plate 26, again to form the plate 27, which is bent back on itself to form the plate 28. This plate 28 is bent at right angles to form the plate 29, which is bent back on itself at 30 and this extension is bent to form the plate 31, which in turn is bent back on itself at 32.

It will be seen that the jamb is formed of three independent vertical plates so formed as to form the complete jamb, and that one

of these plates forms the outer jamb portion 33, while the second one forms a channel 34, and that the second plate in combination with the third plate forms a tubular well 35 with the vertical slot 36 opening toward the window sash.

A vertical parting strip 37 mounted on the second of these formed plates serves to close the channel 34, leaving only vertical slot 38 and also partly closes the vertical slot 36. It will be noted that this construction of plates and parting strips forms two vertical tubular wells, these wells being exterior of the jamb itself but partially formed by the outer walls of the jamb. Side plates 39 and 40 on window sash 41 and 42, respectively, are mounted for vertical movement in these slots and two portions 43 of each plate are thrown out to form bearing points against the walls of the tubular wells to guide the window sash.

It will be seen that the parting strip can be removed by taking out the screws 44 and that by taking out the screws 45 the entire inner wall of the jamb, back to the point 13, can be moved upwardly as viewed in Figure 6 swinging the sash with it, thus allowing ready removal of the sash and complete access to the interior of the jambs. The two weight chain pulleys 46 and 47 (see also Figure 5) are carried by the mounting block 48, which is mounted on the top jamb and lintel connecting casting 5 by the single screw 49 so that a broken pulley may readily be replaced.

The lintel, better shown in Figure 4, is of the same type of construction, the main top and side portions being formed of a single sheet of metal 50. An angle 51, together with the plate 52, is fashioned to form a tubular compartment 53 and passes horizontally across the bottom of the lintel as the plate 54, then vertically upward at 55 where it is formed back and united to plate 50 by screws 56. This tubular compartment 53 serves the same function with regard to the upper sash plate 57 as do the vertical tubular wells of the jamb.

The castings 5 are recessed or rabbetted out around their perimeter to receive the jambs and sill, as shown in Figures 4, 5 and 9, so that the jamb is rigidly fastened to this casting, as is likewise the sill, thereby giving a firm and solid joint between jamb and sill and at the same time presenting a pleasing appearance where the casting and sill and jamb meet.

The window sash 41 is formed of the side plates 39 to which are fastened vertical Z bars 58 and in the channel formed thereby the glass 59 is suitably mounted, ordinarily with some form of cement.

The upper sash rail consists of the plate 57 to which is fastened the plate 60 formed at right angles into a meeting plate 61 at the

top and at the bottom into a plate 62, which, with the plate 57, forms a channel to receive the glass.

The lower rail is formed of the plate 63 which has fastened thereto the plate 64 70 formed at right angles to make the plate 65 and again upwardly at right angles to form the plate 66.

The plate 64 is formed at 67 to form with the plate 63 the channel for the glass and is 75 also formed over at right angles to form the horizontal plate 68 which is brought down at the lip 69.

The upper rail of the lower sash has the plate 70 formed with a lip 71 similar to the lip 69 and adapted to lock therewith, and the other edge is formed downwardly into the plate 72, which is joined with the plate 73 with a spacing channel 74 therebetween forming the upper channel for the sash of 85 the lower glass.

Muntin strips where used are formed of two plates 75 and 76 with spacing channels 77 therebetween, thereby forming channels 90 to receive the glass.

The lower rail of the lower sash is formed of the plate 78 to which is joined the plate 79, formed at 80 into a channel to receive the glass, and at its lower edge is bent to form the plate 81, which is bent downwardly to 95 form the lip 82, which meets the sill at 83.

The top rail of the lower sash carries the Z bar 84 which has a weather strip 85 carried thereby which meets the lip 66 of the meeting rail of the upper sash.

This form of sash construction provides a sash of unusual thinness without sacrificing strength and rigidity and also provides a thin muntin strip, making an unusually 105 pleasing appearance from either side of the window. Also the construction of the jambs and the lintel gives a much greater rigidity and strength than has heretofore been obtained in hollow jambs formed of sheet metal.

In the case of the jambs this rigidity comes from the formation of the tubular wells, while in the lintel it is obtained through the formation of the hollow compartment, in either case the construction being much more rigid than as if the sash plates were allowed to enter the jamb through a vertical slot instead of being housed within wells and compartments exterior of the hollow jambs and lintels.

While we have described our invention and illustrated it in one particular design, we do not wish it to be understood that we limit ourselves to this construction, as it is evident the application of the invention may be varied in many ways within the scope of the following claims:

1. In a hollow frame a hollow jamb formed of three vertical metal plates, the first of said plates being formed into a sub-

stantially **C** shaped cross section and having one end of the **C** formation formed back on itself and continued into a substantially **U** shaped formation, a second plate formed in-
 5 to a substantially channel shape, having a lip meet the extreme end of said **U** shaped formation and having its opposite edge formed to form one wall of a tubular well, said third plate uniting with the outer edge of said
 10 second plate and formed to form the other walls of said tubular well, said plate extending therefrom and formed to meet the opposite end of the **C** shape of said first named plate.

15 2. In a metal window frame the combination with a bent plate forming the exterior wall of a hollow jamb, of a second plate joined to said first named plate to form part of the interior wall of said hollow jamb, said
 20 second named plate being bent to form a vertical channel exterior of said jamb, and a plate joined to said last named plate and covering part of said channel forming a vertical tubular well having a vertical slot
 25 therein.

3. In a metal window frame the combination with a hollow jamb having a vertical tubular well and a vertical channel formed by the exterior surface of the inner wall
 30 thereof, of a flat parting strip carried by said inner wall and extending well beyond the adjacent wall of said channel and partly closing said channel to form thereby the second tubular well, each of said wells having vertical slots opening therefrom, window
 35 sash having side plates extending into said wells through said vertical slots.

4. In a hollow jamb the combination with a vertical plate forming the outer and front and rear walls of said jamb, of an inner wall for said jamb detachably joined to said first named plate and having formed therein a vertical tubular well positioned exteriorally of said jamb to facilitate the removal of
 45 sash carried by said jamb.

5. In a metal window frame the combina-

tion with a vertical plate bent to form the front, rear, and outer wall of a hollow jamb of two plates joined and bent to form the inner wall of said jamb, a parting plate carried by one of said inner wall plates, said inner wall plates being bent to form with said parting plate two vertical tubular wells exterior of said jamb, said parting plate being detachably fastened to said inner wall 50 plate and said inner wall plate being detachably fastened to said outer wall plate.

6. In a metal window construction a lintel having a horizontal semi-tubular frame and having carried below and exterior thereof a 60 horizontal compartment with a horizontal slot extending therefrom to receive the top plate of a window sash.

7. In a metal window frame a lintel having a horizontal semi-tubular portion, joining 65 means for connecting said lintel with a jamb, and a detachable pulley mounting block mounted on said joining means.

8. In a window sash and frame construction the combination of an upper sash and a 70 lower sash, the bottom rail of said upper sash having a plate extending horizontally therefrom and formed downwardly into a lip, the upper rail of said lower sash having a plate formed horizontally therefrom and 75 then downwardly into a lip adapted to engage with said first named lip, an extension of said first named plate extending horizontally from said lower sash and then formed upwardly, a **Z** shaped horizontal bar carried 80 by said upper rail of said lower sash and having a weather strip thereon adapted to meet with said last named extension of said lower rail of said upper sash.

9. In a metal window frame having a lintel and a jamb, means for joining said lintel and said jamb to form a corner and a detachable pulley mounting block mounted at said corner.

CLAUDE D. ENOCHS.
